DESIGN FOR A BRACE FOR SCREEN DOORS AND THE LIKE

Ernest R. Erickson, Des Moines, Iowa, assignor to C. E. Erickson Company, Incorporated, Des Moines, Iowa, a corporation of Iowa

Application June 7, 1937, Serial No. 69,712

Term of patent 3½ years

To all whom it may concern:

Be it known that I, Ernest R. Erickson, a citizen of the United States and a resident of Des Moines, in the county of Polk and State of Iowa, have invented a new, original, and ornamental Design for a Brace for Screen Doors and the Like, of which the following is a specification, reference being had to the accompanying drawing, forming part thereof.

3—3 of Figure 1.

I claim:

The ornamental design for a brace for screen doors and the like substantially as shown.

ERNEST R. ERICKSON.
